DESIGN FOR A KEY

Herbert Jennie Lasky, New York, N. Y.

Application September 27, 1944, Serial No. 115,474

Term of patent 7 years

(Cl. D50—4)

To all whom it may concern:

Be it known that I, Herbert Jennie Lasky, a citizen of the United States of America, residing in New York city, county of New York, and State of New York, have invented a new, original, and ornamental Design for a Key, of which the following is a specification, reference being had to the accompanying drawing, forming part thereof.

The figure on the drawing is a perspective view

of a key showing my new design. The dominant feature of my design resides in the portions shown in solid lines.

The face of the key, not shown, is the same as that illustrated in the drawing.

I claim:

The ornamental design for a key, substantially as shown and described.

HERBERT JENNIE LASKY.
